UNITED STATES PATENT OFFICE.

JOSEPH BLASCHECK, OF WESTCLIFF-ON-SEA, ENGLAND, ASSIGNOR TO BLASCHECK PATENTS LIMITED, OF LONDON, ENGLAND, A COMPANY OF THE UNITED KINGDOM OF GREAT BRITAIN AND IRELAND.

COLLAPSIBLE HUT AND OTHER COLLAPSIBLE STRUCTURE.

1,392,110. Specification of Letters Patent. Patented Sept. 27, 1921.

Application filed March 21, 1921. Serial No. 454,215.

To all whom it may concern:

Be it known that I, JOSEPH BLASCHECK, a subject of the King of England, residing at Westcliff-on-Sea, England, have invented 5 certain new and useful Improvements in and Relating to Collapsible Huts and other Collapsible Structures (for which I have filed an application in England Jan. 13, 1920), of which the following is a specification.

10 This invention relates to huts, sheds and the like of the kind in which the floor or bottom, side and end walls and roof or top are hinged together so as to be readily collapsed without separating the parts thereof 15 and has for its object improvements whereby such structures, furniture, and theatrical scenery (all of which are hereinafter deemed to be included in the word "hut") can be more readily collapsed for transport or storage, and their subsequent reerection facilitated.

Advertising novelties, toys, Christmas cards and the like representing similar objects in miniature are similarly constructed.

25 According to the improved hut, the floor, walls and roof are each complete in themselves and are hinged together in such a way that when in their erected position they mutually support each other and impart 30 great rigidity to the structure. To this end the lower edges of the side walls are hinged to the corresponding edges of the floor, in such a manner as to enable one of them to be turned inward so as to lie flat on the said 35 floor and the other to be turned outward and to also lie flat but with its upper edge directed away from the other side. The roof is hinged to the upper edge of the inwardly 40 folding side so as to extend in the same direction as the outwardly folding side wall when the structure is collapsed and the end walls are hinged to the vertical edges of the 45 outwardly folding side wall in such a manner as to enable them to be turned inwardly when the structure is collapsed. The outer edge of the roof is connected with the upper edge of the opposite side wall by one or more cords or equivalent parts that can be tightened.

50 With this arrangement it will be understood that when the end walls are in position between the parts a perfectly rigid structure

is provided. If it is desired to provide the hut with a gable, the roof may be hinged in the center and the upper edges of the end 55 walls are of angular formation.

It will be understood that the windows and doors of the hut may be formed in its walls in the usual way.

When it is desired to collapse the hut, the 60 end walls are turned inward on their hinges and the side walls, floor and roof folded up.

In constructing a miniature hut according to the present invention to form a Christmas card, advertising novelty, toy or the like, the 65 floor part may be stuck or otherwise secured to a board upon the upper surface of which flower beds, lawns and paths, advertisements or other matter may be printed. Strings may also be attached to the outer edge of the 70 roof, and passed through holes near the upper edge of the adjacent side wall to a suitable point near the outer edge of each of the end walls to which they are respectively made fast, leaving free ends that pass through 75 holes in the side wall adjacent to the free edge of each of the end walls when in their proper positions. With this arrangement the end walls are hinged to the upright edges of the front wall which, when collapsed is 80 folded outwardly so as to lie on its face. The end walls are turned inwardly on their hinges and in so doing draw the free ends of the strings through the holes in the rear wall at the same time leaving the string be- 85 tween the end walls and the free edge of the roof slack so as to enable the rear wall and the roof to be straightened out and folded over the end and front walls.

In practice the collapsing of the miniature 90 is effected by pressing the free edges of the end walls inwardly and folding the other member over the front wall as hereinbefore explained.

In order to reerect the miniature hut, the 95 ends of the aforesaid strings are pulled and so cause the parts to assume their erected positions.

It will be observed that the floor, walls and roof of the miniature hut can be formed 100 out of one piece of card-board or other suitable material creased so as to form hinges when desired. It will also be observed that the outer side of the walls and roof are on

the same side of the card enabling the pictorial details of the hut, advertisements or other matter to be printed on them all together.

5 I will now proceed to more particularly describe my invention with the aid of the accompanying drawings in which:—

Figure 1 is a front elevation of a collapsible miniature house constructed in accordance with the present invention.

10 Fig. 2 is an end view of same.

Fig. 3 is a similar view to that shown in Fig. 2 in which the end walls are hinged inwardly, and the roof raised preparatory to 15 collapsing the structure.

Fig. 4 is an edge view showing the structure collapsed, and

Fig. 5 is an outside view of a blank from 20 which the miniature house illustrated by Figs. 1 and 2 is constructed, laid out flat.

According to the construction illustrated by Figs. 1 to 5 the miniature house is constructed from a blank (illustrated by Fig. 5) composed of cardboard or other suitable sheet material creased at the parts indicated by the dotted lines *q*. These blanks are preferably cut out of a sheet upon which the pictorial details and other matter appearing on the exterior of the house are first printed or otherwise produced. The floor *a*, front wall *b*, rear wall *d*, roof *f*, and end walls *h*, *i*, are folded upon the creases *q* into the positions shown in Figs. 1 and 2 of the drawings, and the floor *a* cemented or otherwise secured 35 to a base *r* of similar material shown in Fig. 2 upon the upper surface of which flower-beds, lawns and paths, advertisement or other matter may be printed or otherwise produced.

40 A string *s* is secured to the roof *f* and passes through holes *t* in the front wall *b*, the end walls *h*, *i*, and the rear wall *d*. This string is secured to the inside of the end walls *h*, *i*, such as by means of a knot (not shown) at a point which enables the string to be pulled taut when the said end walls are in the positions shown in Figs. 1 and 2 of the drawings. With this arrangement the miniature house is erected in the following 45 manner by pulling both ends of the string *s* which by turning the end walls *h*, *i*, on their hinges raises the rear wall *d* into a perpendicular position and by lowering the outer edge of the roof *f* causes it to rest upon the 50 upper edge of the front wall *b*.

The house may be provided with a porch *u* formed from a blank cut out of sheet material and suitably creased and cemented or otherwise secured to the front wall *b* and 55 base *r* of the structure.

60 It will be understood that the walls, floor and roof of the hut may be composed of separate pieces of material and attached to each other by cloth, metal, or other suitable 65 hinges, and any of the said parts—such as

the walls may be provided with windows or doors through which access can be had to the interior of the structure.

I claim:

1. A collapsible structure comprising a 70 floor part, opposite walls hinged to the corresponding edges of said floor part, walls extending between the ends of the aforesaid walls hinged to the vertical edges of one of them, a roof hinged to the upper edge of the 75 wall opposite the one to which the end walls are hinged and across which it extends, holes near the top of the wall adjacent to the outer edge of the roof also near the outer edge of the end walls and in that part of the 80 wall adjacent to the outer edge of said end walls when in their erected positions, and cords attached to the outer edge of the roof passing successively through one of the holes in the adjacent wall and afterward through 85 the hole in one of the end walls to which it is attached and finally through the hole in the wall adjacent thereto when the structure is in its erected position substantially as set forth.

90 2. A collapsible structure comprising a floor part, a long wall hinged to the corresponding edge of said floor part, to enable said wall to be folded inwardly so as to lie upon said floor, the other long wall hinged 95 to the opposite edge of the floor to enable such wall to be folded outwardly; end walls hinged respectively to the opposite vertical edges of the outwardly folding wall to enable them to be folded inwardly upon it, a 100 roof composed of parts hinged together to enable it to conform to the contour of the upper edge of the end walls and hinged to the upper edge of the inwardly folding wall to enable it to be opened outwardly, and ex- 105 tending across the outwardly folding wall, holes near the top of the wall adjacent to the outer edge of the roof also near the outer edge of the end walls and in that part of the wall adjacent to the outer edge of said end walls when in their erected positions and cords attached to the outer edge of the roof passing successively through one of the holes in the adjacent wall and afterward through 110 the hole in one of the end walls to which it is attached and finally through the hole in the wall adjacent thereto when the structure is 115 in its erected position substantially as set forth.

3. A collapsible structure comprising a 120 floor, walls and roof formed integrally of a piece of sheet material creased to form hinges on the lines where the long sides join the floor, at the vertical sides of one of the said long sides where it joins the end walls 125 and at the upper edges of the other long wall where it joins the roof, pictorial details and other markings on the side of said sheet of material forming the outer walls and roof of the structure, holes near the top of the wall 130

adjacent to the outer edge of the roof also near the outer edge of the end walls and in that part of the wall adjacent to the outer edge of said end walls when in their erected 5 positions and cords attached to the outer edge of the roof passing successively through one of the holes in the adjacent wall and afterward through the hole in one of the end walls to which it is attached and finally 10 through the hole in the wall adjacent thereto

when the structure is in its erected position substantially as set forth.

In testimony whereof I have signed my name to this specification in the presence of two subscribing witnesses.

JOSEPH BLASCHECK.
